UNITED STATES PATENT OFFICE.

THEODORE R. WEIDEMANN, OF JERSEY CITY, NEW JERSEY.

HAND-BAG.

No. 905,034.

Specification of Letters Patent. Patented Nov. 24, 1908.

Application filed April 30, 1908. Serial No. 430,065.

To all whom it may concern:

Be it known that I, THEODORE R. WEIDEMANN, a citizen of the United States, and a resident of Jersey City, in the county of 5 Hudson and State of New Jersey, have invented a new and Improved Hand-Bag, of which the following is a full, clear, and exact description.

The invention relates to packing and 10 storing vessels, and its object is to provide a new and improved hand bag, arranged to provide a large main compartment and a plurality of supplementary compartments for the storage of money, visiting cards, 15 handkerchiefs and other articles, to which convenient access can be had without opening or otherwise disturbing the main compartment.

The invention consists of novel features 20 and parts and combinations of the same, which will be more fully described herein-after and then pointed out in the claim.

A practical embodiment of the invention 25 is represented in the accompanying drawings forming a part of this specification, in which similar characters of reference indicate corresponding parts in all the views.

Figure 1 is a perspective view of the improvement in a closed position; Fig. 2 is a 30 similar view of the same in an open position; and Fig. 3 is a transverse section of the same and showing the small pocket book detached from its support.

The hand bag is provided with a main 35 compartment A having a suitable closing frame A' of the usual construction, and on the sides of the said main compartment A are arranged pockets B, B' having their sides extended upwardly to form extension flaps 40 C, C', reaching a desired distance beyond the top of the frame A. On the inner face of the extension flap C are arranged compartments D, D', and a supplementary compartment D² is arranged on the inner face of the 45 flap C', and a small pocket book D³ or the like may be detachably secured on the compartment D. Now the several compartments D, D', D² and D³ may be used for storing money, visiting cards, handkerchiefs, manicure tools, hair pins and other articles, it 50 being understood that convenient access can be had to any one of the compartments with-

out disturbing the others or the main compartment. As the extension flaps C, C' reach beyond the top of the frame A' and 55 the frame A' when closed gives a peak-shaped appearance to the upper end of the main compartment A, it is evident that sufficient space is provided to readily accommodate the compartments D, D', D² and D³ 60 without rendering the hand bag bulky when the flaps C and C' are in a closed position, as shown in Fig. 1.

The flaps C, C' are provided with bow-shaped handles E, E', to permit of the user 65 conveniently carrying the hand bag about, and on the flap C is secured a closing strap F adapted to be passed over the top edge of the other closing flap C' to the outer face thereof, the said closing strap F and the flap 70 C' being provided with suitable fastening devices G for fastening the free end of the closing strap F in position on the flap C'. The closing strap F is attached to the flap C at or near the middle thereof, so as to securely fasten the flaps C and C' together. 75

The hand bag shown and described is very simple in construction, highly ornamental, and is provided with a large number of compartments in a very compact form. 80

Having thus described my invention, I claim as new and desire to secure by Letters Patent:

A bag or similar article comprising a main compartment and side pockets, the 85 outer sides of the pockets being extended upwardly beyond the main compartment, and provided on the inner faces with supplementary compartments, a closing frame for the main compartment, a closing flap for the extended sides, said flap being secured to one of the sides and provided with means at the free end thereof for securing it to the other side, and bow-shaped handles on the extended sides, the closing flap passing through 90 the handles. 95

In testimony whereof I have signed my name to this specification in the presence of two subscribing witnesses.

THEODORE R. WEIDEMANN.
